UNITED STATES PATENT OFFICE.

FRANK A. WELLS, OF NEW YORK, N. Y.

DESIGN FOR A WASHSTAND.

SPECIFICATION forming part of Design No. 32,887, dated June 26, 1900.

Application filed May 29, 1900. Serial No. 18,464. Term of patent 7 years.

To all whom it may concern:

Be it known that I, FRANK A. WELLS, a citizen of the United States, and a resident of New York city, borough of Manhattan, in the 5 State of New York, have invented and produced a new and original Design for Washstands, of which the following is a specification, reference being had to the accompanying drawings, forming part hereof, wherein—

10 Figure 1 is a front elevation of a washstand embodying my invention; and Fig. 2 is a side elevation thereof, partly broken.

15 The leading feature of my design consists in a washstand in which the outer surface of the wall that depends from the table has a configuration of substantially-ogee form extending vertically, and above the table the side edges of the back are in ogee form.

20 In the drawings the letter A indicates the table of the washstand, from which the wall

B depends at the front and two ends, the outer surface of which wall has a convexly curved portion b, concave curves at c and d above and below the same, and a lower curved base f, the general surface configuration in a vertical direction being substantially in ogee form, extending symmetrically along the front and sides of the wall. 25

The back C above table A has its side edges curved convexly at g, concave at h i above 30 and below the portion g, and convexly at j k, substantially in double-ogee form.

Beneath the wall B are legs or pedestals D.

I claim—

35 The design for a washstand substantially as herein shown and described.

FRANK A. WELLS.
